UNITED STATES PATENT OFFICE.

GEORGE S. LEWIS, OF SPRINGFIELD, MASSACHUSETTS, ASSIGNOR TO J. STEVENS ARMS COMPANY, OF CHICOPEE FALLS, MASSACHUSETTS, A CORPORATION OF MASSACHUSETTS.

REAR SIGHT FOR FIREARMS.

1,338,382.

Specification of Letters Patent. Patented Apr. 27, 1920.

Application filed October 2, 1919. Serial No. 327,865.

To all whom it may concern:

Be it known that I, GEORGE S. LEWIS, a citizen of the United States, residing at Springfield, in the State of Massachusetts, have invented certain new and useful Improvements in Rear Sights for Firearms, of which the following is a specification, reference being had to the accompanying drawings, forming a part hereof.

10 This invention has for its object to provide an improved rear sight adapted for easy adjustment for elevation. The sight has been developed in connection with a target pistol but is capable of application 15 to other firearms.

In the accompanying drawing in which the invention is illustrated—

Figure 1 is a view in side elevation of a pistol to which the improved sight is applied.

20 Figs. 2, 3, 4 and 5 are detail views of the improved sight.

The pistol shown in the drawing is designed particularly for use as a target pistol and comprises a frame a , with grip pieces a^2 secured by bolts a^3 , and a barrel b secured in its sleeve or carrier b' which is pivoted in the frame at b^2 . The improved rear sight g is shown as mounted on 30 the frame near its rear end, the maximum distance between the front sight and the rear sight being thus secured. The rear sight comprises a notched member g' carried by an arm g^2 which is pivoted at its forward end g^3 on a pin g^4 mounted in a block g^6 . The notched member g' bears at one end against a clamping screw g^7 which is threaded in the corresponding member of the block g^6 and has formed in its other end 40 a slot g^8 which is engaged by an eccentric

pin g^9 carried in the face or end of a screw or rotatable body g^{10} threaded or mounted in the other member of the block g^6 . For the purpose of adjusting the sight the screw g^7 is backed off slightly so as to relieve the movable member g' , g^2 of pressure and the screw g^{10} is then rotated so as to raise or lower the notched end of the sight as required. When the required adjustment has been effected the screw g^7 is again set 50 up to hold the sight in its adjusted position.

I claim as my invention:

1. In a firearm, the combination of a sight block, a slotted sight pivotally mounted in the block, and a rotatable device mounted in the block and having in its end an eccentric pin to engage the slot in the side of the movable sight. 55

2. In a firearm, the combination of a sight block, a sight pivotally mounted in the sight block, means to adjust the position of the sight, and a binding screw threaded in the sight block and arranged to bear against the side of the pivoted sight to retain it in 60 position. 65

3. In a firearm, the combination of a sight block having two side members, a sight pivoted between the two side members and having a longitudinal slot in one side thereof, 70 a clamping screw threaded in one side of the sight block and arranged to bear against the pivoted sight, and a screw threaded in the other member of the sight block and having an eccentric pin to engage the slot 75 in the side of the pivoted sight.

This specification signed this 29th day of September, A. D. 1919.

GEORGE S. LEWIS.
